UNITED STATES PATENT OFFICE.

FRANK C. DORMENT, OF WELLINGTON, OHIO, ASSIGNOR OF ONE-HALF TO ALBERT T. FLETCHER, OF WASHINGTON, DISTRICT OF COLUMBIA.

ATOMIZER.

Application filed September 21, 1923. Serial No. 663,968.

This invention relates to valveless atomizers and has for its object to provide an atomizer in which the bulb itself serves as a container for the liquid so that the atomizer can be operated with one hand and which operates efficiently as long as any liquid remains in the bulb.

A further object is to provide an atomizer of the type above described in which complete compression of the bulb is permitted without danger of breaking the liquid tube within the bulb and in which the nozzle may be bent with respect to the bulb without breaking the liquid tube.

15 A further object is to provide an atomizer in which the bulb serves as a container which will deliver a spray when held at various angles.

20 A further object is to provide novel means for controlling the discharge of liquid and air and for causing the air to be so directed into the stream of liquid as to produce a finely divided spray.

25 A further object is to provide a bulb atomizer in which the liquid is discharged in the form of a spray instantly upon application of pressure to the bulb and which requires little effort to operate.

30 A further object is to provide an atomizer in which the liquid will not leak from the nozzle when the atomizer is held in inverted position.

35 A further object is to provide a novel means for maintaining the end of the liquid discharge tube in engaging relationship with the interior of the nozzle head.

40 A further object is to provide an atomizer which is cheap to manufacture, which is of a form convenient to carry, occupies little space, is easy to fill and can be readily cleaned.

Other objects will be apparent from the following description and accompanying drawings.

45 The following description and accompanying drawings set forth in detail certain means embodying the invention, the disclosed means, however, constituting but one of the various mechanical forms in which the principle of the invention may be employed.

Referring to the accompanying drawings

forming a part of this specification, Fig. 1 is a longitudinal section through the bulb and nozzle; Fig. 2 is a section similar to Fig. 55 1 showing the position of the parts when air or liquid is being drawn into the bulb through the nozzle by expansion of the bulb, the movement of the tube being shown on an exaggerated scale; Fig. 3 is a view showing 60 the nozzle parts and inner tube detached; Fig. 4 is a section on line 4-4 of Fig. 1.

Referring to the accompanying drawings, the atomizer consists of an oval shaped bulb 1 of soft rubber which is provided at one 65 end with a supporting base 2 formed by an annular outwardly and downwardly inclined relatively thin flange integral with the body of the bulb and a nozzle 3 secured within an opening in the opposite end of the 70 bulb. The soft rubber base flange 2 conforms to the shape of the hand and does not in any way interfere with the gripping of the bulb and readily yields when the bulb is compressed. The nozzle 3 has an enlarged 75 inner end 4 adapted to be forced through the opening in the end of the bulb and providing an annular shoulder which engages with a shoulder formed on the inner side of the bulb surrounding the opening therein. The 80 nozzle is provided with a second enlarged portion 5 providing an annular shoulder which engages the like shoulder on the bulb surrounding the outer end of the opening 85 therein. The outer enlargement 5 is tapered inwardly from the shoulder on the outer side thereof and the bulb is formed with an integral collar portion 6 adapted to be stretched over the enlargement 5 whereby the nozzle is more firmly held in place and 90 the sharp edge of the enlargement 5 is covered. Screwed into the outer end of the body portion of the nozzle 3 is a nozzle head 7 which has a bore of slightly less diameter than the bore of the body portion of the 95 nozzle and is provided at its outer end with a restricted opening 8 disposed axially of the bore.

The head 7 is slightly tapered to receive an outer removable nose piece 7^a which is 100 frictionally held thereon so that it can be readily removed to permit insertion of the nozzle into smaller passages, as for instance the nasal passages. The outer end of the

nose piece 7^a is flush with the outer end of the head 7 so that it does not affect the spray and will not catch liquid falling back from the spray.

5 For controlling the discharge of air and liquid from the bulb an inner rigid tube 9 is slidably mounted within the nozzle. The inner tube 9 is provided with an axial passageway 10 which is adapted to register 10 with the opening 8 in the head of the nozzle. The tube 9 has a square outer end portion 11 which fits slidably within the head 7 of the nozzle so that the passageway 10 is always held in alignment with the aperture 8 and providing exterior passageways between the flat side and the interior of the head 7. The inner end of the tube 9 projects into the bulb 1 and has attached thereto a flexible rubber tube 12 which is long 15 enough to extend from the inner end of the tube 9 to the opposite end of the bulb.

The interior of the nozzle head 7 at its outer end tapers inwardly to the central opening 8 forming a conical seat 13 against 20 which the squared end 11 of the inner tube is adapted to abut and forming with the squared end 11 segmental openings through which air is directed inwardly into the liquid stream issuing from the passageway 10 25 breaking up the stream so that it issues from the nozzle in a fine spray.

The open end of the flexible tube 12 extends into the liquid within the bulb and serves to normally hold the tube 9 in engagement with the seat 13. Whenever pressure is exerted upon the body of air within the bulb by gripping the bulb, pressure upon the liquid forces the liquid up through the tube 12 and through the small passageway 40 10 in the tube 9. The air pressure thus exerted upon the body of liquid in the bulb, causes the liquid to flow through the tube 12 and passageway 10, through the discharge aperture 8, and air to flow through the outer passageway and through the segmental openings into the liquid stream, discharging the liquid in a finely divided spray, due to mixture of air and liquid and in a steady stream. When the bulb is released it will gradually 45 expand to its normal shape reducing the air pressure within it and drawing air through the nozzle opening 8. The pressure of the air entering the opening 8 will force the tube 9 away from the opening so that the air can 50 pass freely through the passageway between the tube 9 and the inner wall of the nozzle to the interior of the bulb. The air is thus permitted to enter the bulb freely so that the bulb will quickly expand to its normal shape. 55 When the wall of the bulb is squeezed inwardly against the tube 12, the tube will readily bend to conform to the inwardly pressed wall and the open end of the tube 60 will remain in the end of the bulb toward 65 which the liquid is forced by air pressure

so that the bulb may be tilted to various angles with respect to the vertical while in use.

The bottom of the bulb is preferably rounded so the liquid contents can be completely discharged even when the bulb is held at an angle to the vertical. 70

The inner open end of the tube 12 is preferably cut on a bias so that the tube cannot be sealed by engagement of the end thereof with a portion of the bulb. A further advantage of the inner tube arrangement is that it permits the bulb to be held with the nozzle in inverted position without permitting the liquid to leak through the nozzle 80 since when the nozzle is inverted the tube 9 which normally engages the head 7 substantially cuts off communication between the outer passageway and the opening 8. 85

To fill the bulb, the bulb is compressed and 90 dipped in the liquid and released. Upon squeezing and releasing the bulb the desired quantity of liquid will be quickly drawn into the bulb through the relatively large outer passageway between the interior of the body 95 of the nozzle and the inner tube 9.

To protect the nozzle and to prevent leakage when the device is being carried in a case or in the pocket a soft rubber cap 14 such as shown in Fig. 4 may be secured upon 95 the head 7 of the nozzle.

Having described my invention, I claim:

1. An atomizer comprising a flexible bulb, a discharge nozzle attached thereto, said nozzle having a contracted discharge opening 100 in the end thereof, a tube slidably mounted within the nozzle and projecting into the bulb, said tube having a passageway there-through registering with the discharge opening of the nozzle, and yieldable means for pressing said tube toward the discharge end 105 of the nozzle.

2. An atomizer comprising a flexible bulb adapted to contain liquid, a nozzle secured to one end of the bulb, said nozzle having a contracted discharge opening, a rigid tube slidably mounted in said nozzle and provided with a passageway registering with the discharge opening, and a flexible tube connected to the inner end of said rigid tube, said flexible tube extending to the end of the bulb opposite that to which the nozzle is attached 110 and serving to yieldably support the rigid tube. 115

3. An atomizer comprising a flexible bulb, a discharge nozzle attached thereto, said nozzle having a contracted discharge opening, a tube slidably mounted in the nozzle and projecting into the bulb, means for yieldably urging said tube into engagement with the 120 end of the nozzle, said tube having a passageway registering with the discharge opening and an end portion normally engaging the end of the nozzle around the opening, said tube having a transverse cross sectional 125 130

shape different from that of the nozzle passageway whereby an outer passageway for fluid is provided between the exterior of the tube and the nozzle wall, said tube being movable away from the end of the nozzle by the pressure of incoming liquid to fully open said passageway and permit liquid to pass freely to the interior of the bulb, when the

bulb has been collapsed for refilling purposes, said tube being normally movable into engagement with the end of the nozzle to substantially close the outer passageway when liquid is forced from the bulb. ¹⁰

In testimony whereof, I hereunto affix my signature.

FRANK C. DORMENT.
